Everett K. Wolfe
BY Walton Harrison,
his ATTORNEY

UNITED STATES PATENT OFFICE.

EVERETT K. WOLFE, OF WESTCHESTER, NEW YORK.

BOTTLE-PROTECTOR.

1,338,063.

Specification of Letters Patent. Patented Apr. 27, 1920.

Application filed February 4, 1918. Serial No. 215,232.

To all whom it may concern:

Be it known that I, EVERETT K. WOLFE, a citizen of the United States, residing at Westchester, in the county of Bronx and 5 State of New York, have invented certain new and useful Improvements in Bottle-Protectors, of which the following is a full, clear, and exact description.

My invention relates to bottle protectors, 10 of a kind suitable for protecting nursing bottles while being heated, and while being handled by an infant.

More particularly stated, I seek to make my improved bottle protector principally of 15 wire, so arranged as to afford a maximum of protection due to heat or to blows or shocks, the device being in two parts which are separable in order to facilitate the introduction and removal of the bottle at the will of the 20 operator.

Reference is made to the accompanying drawing, forming a part of this specification, and in which like reference characters indicate like parts in the several figures.

25 Figure 1 is a side view, partly in elevation and partly in section, showing my device as used with a nursing bottle of ordinary form.

Fig. 2 is a plan view of the same.

Fig. 3 is a fragmentary perspective, showing 30 one of the snap fasteners for holding together the two separable parts of the device.

Fig. 4 is a section on the line 4—4 of Fig. 1, looking in the direction of the arrows.

35 A spacing ring is shown at 5, and in this instance is made of sheet metal. A number of ribs 6 are each made of wire, and provided at its upper end with an eye 7, the several eyes extending through holes in the 40 spacing ring 5.

Each rib 6 is provided with a curved portion 8, leading down to a waist bend 9. Below this waist bend is a portion 10, having a V-form, the portions 10 together constituting 45 a spider which serves as a base, as may be understood from Figs. 1 and 4.

A waist ring is shown at 11, and engages all of the waist bends 9. The waist ring is in this instance made of a single piece of 50 wire, the ends of which are joined by twisting them together at 12.

The parts thus far described together constitute the main or body portion of my device.

55 I provide a spacing ring 13, having a form similar to that of the spacing ring 5. I also

provide a spacing ring 14, having a shorter cross diameter than that of the ring 5. A number of ribs 15, each provided at its ends with eyes 16, 17, extend from the spacing 60 ring 5 to the spacing ring 14. The eyes are preferably soldered to the spacing rings or secured thereto by pinching, but this is not essential.

The spacing ring 13 carries a pair of snap 65 fasteners 18, each made of sheet metal and held upon it by pins 19 or secured upon it in some equivalent manner. The parts numbered 14 to 19 inclusive together constitute the upper or top member of my device, and 70 is separable from the body portion or lower member thereof.

A nursing bottle is shown at 20. While in this particular instance the bottle has a general cylindrical form and is provided 75 with a lower end which is rounded, it should be understood that bottles of any other form can be employed. With a bottle of the form here indicated, the rounded portion 21 is adapted to rest against the bent portions 8 80 of the ribs 6, so that the weight of the bottle and its contents is supported altogether above the spider or base. Thus the bottle rests upon what is essentially a spring seat. Moreover, the curvature or slant of the portions 8 of the ribs 6, by their form as a slanting support, further protect the bottle as against shocks or violent blows. The neck portion of the bottle extends out through the spacing ring 14 whenever the top or upper 90 member of my device is in position, as shown in Fig. 1. The annular tip 23 of the bottle may be of the usual form to facilitate the attachment of a nipple.

The operation of my device is as follows: 95

The body portion or lower member is placed in a dish or kettle of hot water, and simply rests on the bottom of the vessel. The bottle being filled with modified milk or other liquid food to be fed to an infant, 100 the bottle is placed in the body portion of the device, so as to be supported in the manner above described, and thus kept out of contact with the bottom of the vessel containing the hot water. Thus arranged 105 the bottle cannot readily be cracked from the heat, yet the bottle can be lifted out from time to time, in order to test the temperature or other condition of the contents of the bottle. The food being thus prepared, 110 the top member is placed in position; in other words, the spacing ring 13 is rested on the

spacing ring 5, and the spring fasteners 18 are caused to grip the edge of the spacing ring 5, as shown in Figs. 1 and 2. This done, the bottle and the protector may as a unit be lifted out of the hot water, the nipple placed in position if this has not already been done, and the bottle with its protector may now be handed to the infant, or manipulated by the mother or the nurse, in 10 such manner as to feed the infant from the bottle.

Suppose, now that by accident the bottle is allowed to strike against a bed post or the like, or to drop on the floor. The bottle 15 is protected from danger of breaking, because the bottle does not receive the full force of the blow. The fact is that the bottle is practically spring-supported and spring-cushioned as against almost any violence to 20 which it is likely to be subjected in ordinary use in practice.

I do not limit myself to the precise construction shown, as variations may be made therein without departing from the spirit of 25 my invention as determined by my claims.

I claim—

1. A protector for nursing bottles, comprising a cage member having a number of wires spaced apart in order to inclose the 30 bottle and provided with waist bends, a waist ring inclosing said wires and engaging said waist bends so as to brace the same, thereby forming a waist, the parts being so arranged that said waist ring engages the 35 outer peripheral surfaces of the wires of said cage member, said waist as a whole being curved in order to accommodate the lower end of a bottle rested thereupon, said wires being further provided with a V bend

each, the several V bends together forming a 40 base.

2. A protector for nursing bottles, comprising a cage member having a number of wires spaced apart in order to hold a bottle, each of said wires being provided 45 with a V-bend and with a waist bend, and a waist ring inclosing said wires and engaging each of said waist bends, said waist ring and portions of the wires engaged by said waist ring together forming a waist 50 said V-bend being so located as to extend underneath said waist, and to serve as a spring support for a bottle resting upon said waist.

3. A protector for nursing bottles, comprising a pair of cage members for inclosing the bottle, said cage members being completely detachable relatively to each other, one of said cage members having a spring formation for supporting the weight of the bottle, the other of said cage members having 55 a resilient construction so arranged that when the two cage members inclose the bottle both of said cage members are under slight spring tension due to pressure of the bottle there-upon.

4. A protector for nursing bottles, comprising a pair of wire cage members mated together in order to inclose a bottle, one of said members comprising two rings of different diameter spaced apart, and a number 70 of separate ribs each extending from one of said rings to the other, each rib being made of a single piece of spring wire and having end portions which terminate abruptly, each end portion being curved partially around 75 one of said rings and thus formed into an eye.

EVERETT K. WOLFE.
